FLUE AND BACK DRAFT HOOD FOR GAS RANGES

Filed Feb. 28, 1927

Joseph A. McCarthy,
Inventor

UNITED STATES PATENT OFFICE.

JOSEPH A. McCARTHY, OF JAMAICA, NEW YORK.

FLUE AND BACK-DRAFT HOOD FOR GAS RANGES.

Application filed February 28, 1927. Serial No. 171,564.

This invention relates to a flue and back draft hood for gas ranges, for taking off into the atmosphere, through a building wall, with the opening in close proximity to the oven vent of a gas range, instead of leading same through a flue to the roof, of the products of combustion; and has for its object the prevention of any back draft from extinguishing the combustion chamber flame, thereby causing personal injury; as well as the conservation of oven heat by breaking the draft, thus preventing the forced draft from drawing the heat from the oven with velocity.

With the above objects in view, the invention consists essentially in the arrangement and construction of parts hereinafter more particularly described and later pointed out in the appended claims, reference being had to the accompanying drawing in which:

20 Fig. 1 horizontal section through the flue pipe.

Fig. 2 is top view of Fig. 1.

Fig. 3 back view of conical hood and flanged ring.

25 Fig. 4 support of baffle plate.

Referring to the drawing, the flue comprises an oblong box A having opening 12 with ribs 1 and 2 running laterally, staggered, extending half way from top and bottom respectively of box, and acting as baffles for any back draft from the atmosphere, and a length of pipe 4, sufficiently long enough to extend through the wall of a building, a conical hood 5 on the end of this pipe, within which is a ring 6, with three projecting prongs 8, interlocking and supported in an annular groove 7, said ring acting as a collar for pipe 4 from oven vent of combustion chamber, as well as for a support of baffle plate, 10, mounted on 30 projecting prongs 9, and spaced from the bore of said ring 6, allowing the products of combustion to escape; at the same time breaking the draft, as well as deflecting any back draft into the room, thus preventing the ex-

tinguishing of the combustion chamber flame. 45

Among the advantages of this invention over similar devices are the absolute prevention of any back draft from extinguishing the flame of the combustion chamber of the gas range, as well as the conservation of the 50 heat in the oven by eliminating the forced draft. Other similar devices without this construction are causing accidents daily with attending personal injuries.

I claim:

1. A flue and draft hood for gas ranges and the like comprising an oblong box having an opening into the atmosphere, and staggered baffles running laterally and extending upwards and downwards from top and bottom of box respectively, with a length of pipe attached to said box and adapted to extend through the wall of a building, to which is attached a conical hood on which is an annular groove; a ring with three projecting prongs 65 interlocking and supported in conical hood by said groove.

2. A flue and draft hood for gas ranges and the like comprising an oblong box having an opening into the atmosphere, and staggered 70 baffles running laterally and extending upwards and downwards respectively from top and bottom of box, with a length of pipe attached to said box and adapted to extend through the wall of a building, to which is attached a conical hood on which is an annular groove, a ring mounted in inlet end of pipe adapted to extend through the wall, with three projecting prongs interlocking 75 and supported in conical hood by said groove; 80 with baffle plate spaced from the bore of said ring and supported on three projecting prongs on said groove.

Signed in Jamaica, in the county of Queens, State of New York, this 25th day of 85 February, A. D., 1927.

JOSEPH A. McCARTHY.
